UNITED STATES PATENT OFFICE

KARL WERNER, OF NUERMBERG-EIBACH, GERMANY, ASSIGNOR TO PROGRESS GESELLSCHAFT FUER TEXTILMASCHINEN MIT BESCHRAENKTER HAFTUNG, OF NUERMBERG, GERMANY, A CORPORATION OF GERMANY

LOOM OPERATING DEVICE

Application filed June 27, 1927, Serial No. 201,901, and in Germany March 21, 1927.

This invention has reference to means of increasing the efficiency and the output of mechanical looms by the increase of the number of revolutions of the operating shaft without interfering with the proper opening of the shed required for the passage of the shuttle. The increase of the number of revolutions of the operating shaft in the case of looms presents great difficulties in view of the fact that a certain time must be allowed for the passage of the shuttle through the open shed from one edge of the fabric to the other, the time required varying with the width of the fabric. Comparatively limited degrees of increase of revolutions have been obtained according to the prior art by causing an eccentric chain wheel mounted on the main—or crank shaft of the loom to be operated from a jack shaft or counter shaft by means of a chain wheel, so that at each half revolution the angular velocity of the main shaft of the loom is somewhat increased or diminished. The adjustment of the loom in this case has been such that during the period of great angular velocity the weft was beaten against the fabric, while on the other hand, in accordance with the period of small angular velocity during the passage of the shuttle through the shed the movement of the lay was retarded. Now, inasmuch as the operation of the beating shaft is effected from the main shaft or crank shaft of the loom by a pair of gear wheels, the lack of uniformity of the rotating movement of the main shaft or crank shaft is likewise transmitted to the beating shaft by way of this pair of gear wheels, and, in view of the fact that as a result of the increased number of revolutions a heavier blow is made to act on the shuttle, this blow is still undesirably increased by the fact that it is always effected during the period of increased angular velocity, so that the force of the blow becomes greater than ordinarily admissible, and has to be reduced to the admissible limit by decreasing the eccentricity of the beating eccentric cams.

There is the further drawback that by

the constant undesired accompanying accelerations and retardations of the beating gear and of the shuttle beating shaft causes considerable amounts of energy to be uselessly wasted during the operation of the loom, so that the increased number of revolutions and the resulting increase of efficiency of the loom are only obtained by an unnecessarily large expense of energy. To this should be added the inconvenience that at the moment of the striking of the blow against the shuttle there is always one and the same pair of teeth of the beating gears in engagement with each other, so that these two teeth are rapidly worn out and are very often wholly or partially broken off. This fact results in an excessive consumption of such beating gears in the weaving mills, and has given rise to a number of attempts for the elimination of these difficulties, all of which however have thus far not been able to accomplish any satisfactory practical results.

Now, it is one of the main advantages and objects of my invention to devise means of obviating these drawbacks, and by the means to be described a number of important advantages are likewise produced. The invention will be more fully described and its advantages pointed out by reference to the accompanying drawing showing by way of exemplification an embodiment of the principles of the invention as applied to a mechanical loom in Figure 1 in side elevation and in Figure 2 in plan view.

In the drawing:—A is the main shaft and B is the jack or auxiliary shaft for a train of gearing, and C indicates a bearing or journaling housing for the shafts A, B appropriately secured to the wall D of the loom. The idle pulley E is mounted on the same shaft with the driving pulley F which, by means of the collar G is retained in coupling engagement with the chain wheel H secured to the collar G. The chain wheel H is connected to the chain wheel K by means of the chain J whereby the beating or striking shaft L is operated on which is mounted the chain wheel K,

while at the same time the chain wheel M is mounted on the gear-wheel jack shaft B is likewise operated by means of the chain J the outside of which engages with the wheel 5 M. The wheel M is coupled to the chain wheel N which drives by means of the chain P and the chain wheel O the crank shaft Q. In view of the fact that the chain wheel K is operated by the chain J from the inside of said chain, while the outside of the 10 chain drives simultaneously the chain wheel M the shafts Q and L are rotated in different directions. The chain wheel N or the chain wheel O or both of these wheels 15 may be eccentrically arranged and may be rigidly or adjustably disposed and with or without coupling or clutching means.

By means of the intermediate gear jack shaft B and the peculiar arrangement of 20 the driving chains in accordance with this invention the result is produced that the crank shaft Q and the shuttle beating shaft L are rotated in opposite directions, as required in the case of looms, so that the 25 beating-gear wheels are dispensed with and may be replaced by chain wheels. As appears from the drawing, the chain wheels H, M, K are surroundingly embraced by the chain J in such a manner that the chain 30 is always in engagement with quite a considerable number of teeth and the force required in each particular case, and especially the beating force required for the production of the blow of the shuttle is always 35 distributed over a plurality of teeth, and by this means undue wearing out, as has been common with the gear wheels heretofore employed, becomes entirely excluded.

In view of the fact that the lack of uniformity required for the movement of the lay or batten is produced from the jack shaft B of the intermediate gear wheels and by the eccentric chain wheels N and O, it is only the crank shaft Q which possesses 45 the peculiar angular velocity increasing or diminishing at each revolution, and which is transmitted to the movement of the lay as an accelerating or respectively retarding means, while the beating shaft L which is 50 driven by the chain wheel K, the chain J and the chain wheel H are operated from the shaft A of the main driving gear with uniform angular velocity. In order to obtain the necessary ratio of 1:2 for the number of rotations of the shaft Q and the shaft 55 L the number of teeth of the chain wheels M and K must be in the same proportion, and the wheels N and O must have the same number of teeth.

60 In order to arrive in a simple manner at an increase or a reduction of the number of revolutions of the loom, without the necessity of changing the belt drive of the loom, the chain wheel H is exchangeably connected to the clutch collar G, so as to

admit of being replaced by chain wheels of a larger or smaller number of teeth. In view of the fact that according to this invention only the crank shaft Q performs an accelerated or retarded rotating movement, 70 while the beating shaft L is rotated with uniform circular velocity, a loom according to this invention in spite of an increase in the number of revolutions requires considerably less operating energy than in the case of the accompanying additional acceleration and retardation of the beating gear wheels and of the shuttle beating shaft, which was unnecessarily effected in the devices according to the previous art. In view of the reduction of the parts or masses with not uniformly accelerated and retarded movements, 75 there is the additional possibility of a considerable increase in the number of revolutions and of the resulting efficiency of the 80 loom with a relatively very limited additional expense of energy.

In practice modifications of the specific instruction shown by way of illustration of the principles of the invention may be made 85 without departing from the spirit and scope 90 of the invention, as particularly set forth in the appended claims.

I claim:—

1. In a loom operating device in combination, a main driving shaft, a shuttle-beating shaft, and a jack-shaft intermediate thereof, driving means for the main shaft, a chain connection between the main shaft and the beating shaft, engageable with a member on the jack shaft, and adapted to drive the jack shaft in a direction opposite to that of the beating shaft, an operating crank shaft, and a chain connection between said crank shaft and the jack shaft and eccentric means for increasing and decreasing the velocity of the 95 crank shaft the operative relation of the parts being such that the beater shaft operates the shuttle driving mechanism and the crank shaft operates the lay in timed relation to the shuttle driving mechanism and at a variable speed to provide a slow movement 100 of the lay while the shuttle driving mechanism is operating.

2. In a loom operating device in combination, a main driving shaft, a shuttle-beating shaft, and a jack-shaft intermediate thereof, a chain connection between the main shaft and the beating shaft, a chain wheel on the jack shaft in engagement with the outside 110 of said chain-connection and rotated thereby in a direction opposite to that of the beating shaft, an operating crank shaft, a chain wheel eccentrically mounted on said crank shaft and a flexible connection on said chain 115 wheel, and means on the jack shaft for moving the flexible connection the operative relation of the parts being such that the beater shaft operates the shuttle driving mechanism and the crank shaft operates the lay in 120 125 130

timed relation to the shuttle driving mechanism and at a variable speed to provide a slow movement of the lay while the shuttle driving mechanism is operating.

5. In a loom operating device in combination, a main driving shaft, a shuttle-beating shaft, and a jack shaft intermediate thereof, driving means for the main shaft, a flexible connection between the main shaft and the 10 beating shaft, and adapted to engage with the jack shaft, and rotating the same inversely relatively to the beating shaft, an operating crank shaft, a flexible connection thereof with the jack shaft and an eccentric 15 on the crank shaft and on the jack shaft engaged by said flexible connection, the operative relation of the parts being such that the beater shaft operates the shuttle driving mechanism and the crank shaft operates the lay in timed 20 relation to the shuttle driving mechanism and at a variable speed to provide a slow movement of the lay while the shuttle driving mechanism is operating.

4. In a loom operating device in combination, a main driving shaft, a shuttle-beating shaft, and a jack-shaft intermediate thereof, chain wheels on said shafts, and a flexible connection between the chain wheels of the main shaft and of the beating shaft, driving 25 means coupled to the main driving shaft, the flexible connection engaging with the chain wheel of the jack shaft, an operating crank shaft, a chain wheel eccentrically disposed on the crank shaft and a flexible connection 30 between the chain wheel of the crank shaft and the chain wheel of the jack shaft and adapted to rotate the crank shaft inversely with relation to the rotation of the beating shaft, the operative relation of the 35 parts being such that the beater shaft operates the shuttle driving mechanism and the crank shaft operates the lay in timed relation to the shuttle driving mechanism and at a variable speed to provide a slow movement 40 of the lay while the shuttle driving mechanism is operating.

5. In a loom operating device in combination, a main driving shaft, a shuttle-beating shaft, and a jack shaft intermediate thereof, 45 flexible driving means connecting the beating shaft and the main shaft, and engaging at its outside with the jack shaft and rotating the jack shaft inversely with relation to the beating shaft, a crank shaft, a flexible 50 connection between the crank shaft and the jack shaft and eccentrically disposed wheels 55 engaging the last mentioned flexible connection, and mounted on at least one of the two shafts in engagement with the last mentioned connection, the operative relation of 60 the parts being such that the beater shaft operates the shuttle driving mechanism and the crank shaft operates the lay in timed 65 relation to the shuttle driving mechanism and at a variable speed to provide a slow 70

movement of the lay while the shuttle driving mechanism is operating.

6. In a loom operating device in combination, a main driving shaft, a shuttle-beating shaft, and a jack shaft intermediate thereof, 75 driving means for the main shaft, a chain connection between the beating shaft and the main shaft, a chain wheel on the jack shaft, engaging the outside of the chain connection and driven thereby contrariwise to the rotation of the beating shaft, an operating crank shaft, eccentrically disposed chain wheels 80 respectively mounted on said shaft and the jack shaft, and chain connection between said chain wheels, the operative relation of the parts being such that the beater shaft operates the shuttle driving mechanism and the crank shaft operates the lay in timed 85 relation to the shuttle driving mechanism and at a variable speed to provide a slow movement of the lay while the shuttle driving mechanism is operating.

7. In a loom operating device in combination, a main driving shaft, a shuttle-beating shaft, and a jack shaft intermediate 90 thereof, driving means for the main shaft, a flexible driving connection between the shuttle beating shaft and the main shaft, driving chain wheels engaging said driving connection and respectively disposed on the jack shaft and on the beating shaft and possessing a peripheral ratio of 1:2, an operating crank shaft and a chain wheel eccentrically disposed on said crank shaft and an additional chain wheel on the jack shaft of 95 equal size with the last mentioned chain wheel, and a flexible connection between the two equal last-mentioned chain wheels, the operative relation of the parts being such that the beater shaft operates the shuttle driving mechanism and the crank shaft operates the lay in timed relation to the shuttle driving mechanism and at a variable speed to provide a slow movement of the lay while 100 the shuttle driving mechanism is operating.

In testimony whereof I affix my signature.

KARL WERNER.
